UNITED STATES PATENT OFFICE

130,162

DESIGN FOR A DOUCHE

Frank B. Van Wormer, Niles, Ill.

Application May 21, 1941, Serial No. 101,075

Term of patent 14 years

To all whom it may concern:

Be it known that I, Frank B. Van Wormer, a citizen of the United States, residing at Niles, in the county of Cook and State of Illinois, have invented a new and original and ornamental Design for a Douche, of which the following is a specification, reference being had to the accompanying drawing, forming part thereof.

I claim:

The ornamental design for a douche, as shown.

FRANK B. VAN WORMER.
